UNITED STATES PATENT OFFICE.

EDWARD M. CLARK, OF DAVENPORT, IOWA.

COMMERCIAL SIGN.

Application filed April 26, 1926. Serial No. 104,851.

My invention has reference to commercial signs, of the type set forth in my former application for Letters Patent of the United States filed May 19, 1925, Serial No. 31269.

5 The present invention seeks to improve the manner of construction and arrangement of such signs.

One of the objects thereof is to provide a sheet metal frame or moulding for the 10 sign which is formed of a single sheet of metal, bent into the desired form, by which construction a frame of great strength may be produced, and one in which the cost of production is greatly reduced from that of 15 signs which are produced by present methods.

Another purpose thereof is to provide a novel form of letter plate, the edge of the letter in which is beveled or otherwise 20 turned out of the plane of the main sheet. This not only strengthens the edge of the plate, but when a backing plate for the letters is used, as shown in said former application, the turned edge of the letter bears 25 against the backing plate, forming a more rigid structure, and preventing any rattling sound which might result from a loose contact of such parts. It has been customary in some cases to form a flange on the edge 30 of the letter by means of a strip fastened at an angle therewith by soldering or similar method, but this method is a slow and expensive one.

The production of the letters in the manner mentioned in a simple and inexpensive manner is made possible by means of a machine designed specially for the purpose, and the subject of a companion application for Letters Patent of the United States. By 40 the use of this machine any style of letter or other character can be cut and formed by a continuous operation, or operations. It has been the custom to cut out a letter with a cutting tool, comprising suitable dies and 45 cutters, but each one has been limited to the production of a single letter, and a special type of letter, whereas in the use of said machine any desired style can be reproduced.

50 The above named, and other features and advantages of the invention will more fully appear from the following specification, reference being had to the accompanying drawings, in which:—

55 Fig. 1 is a fragmentary end portion of a sign embodying the invention.

Fig. 2 is a cross-section on the broken line 2—2 of Fig. 1.

Fig. 3 is a cross-section of the moulding 1, enlarged.

The reference number 1 indicates the upper moulding of a sheet metal frame, 2 the lower moulding, and 3 one of the end pieces, properly joined with the first-named sections. The lower moulding is formed with 65 a channel 4, for the support of the lower edges of any desired number of letter plates 5, in rear of which is shown a backing plate 6, of frosted glass or similar material, also supported in the channel 4. The upper 70 edges of the plates 5 and 6 are held in a channel 7 formed on the inner side of the upper moulding 1. The letters are formed by cutting the same from the plate 5, as indicated by the letter E in Fig. 1, the edges 75 of the letter being bent inwardly at an angle of approximately forty-five degrees, as shown at 8, the inturned edges bearing against the outer face of the plate 6, and assisting in providing the rigid construc- 80 tion hereinbefore mentioned.

The mouldings are each provided with a back plate 9, bent forwardly into a cornice comprising a straight band 11 and curved portion 12, ending in a panel 13, formed at 85 its lower edge into a loop 14. In the case of the moulding 1 this loop is continued into the channel 7, the inner edge 15 of which is turned upwardly. The edge 16 of the plate 9 is also turned upwardly, the turned edge 90 thereof being enclosed within the loop 14, and adding strength to the joint formed thereby.

All of the parts above mentioned are integrally formed, such construction doing 95 away with the necessity of riveting or otherwise connecting a number of separate parts, as is now the custom.

The moulding 2 is formed similarly to the moulding 1, except that the channel 7 is 100 given a greater depth than that of the channel 4, so that the plates 5 and 6 can be first inserted in the channel 7, and then lowered into the channel 4, without possibility of their release except by a reversal of the 105 operation.

The edge of the letters in the letter plates can be bent so as to project at any desired angle with the main plate, including a right angle, or they can be turned into a bead 110 or other formation out of line with said plate. These bevels and other formations

are always produced integrally with the plate, by a comparatively simple operation, and without the use of any of the joining or attaching methods hereinbefore referred 5 to.

What I claim, and desire to secure by Letters Patent, is:

1. A sheet metal frame, comprising a back plate having its lower edge turned upwardly against itself, and a cornice formed integrally with said back plate, and having its lower edge rolled round the lower edge of 10 said back plate.

2. A sheet metal frame, comprising a 15 back plate and cornice formed integrally

therewith, and having its lower edge rolled round the lower edge of said back plate, and a channel formed integrally with the rolled edge of said cornice, and having its inner edge turned upwardly upon itself. 20

3. A sheet metal frame, comprising a back plate and cornice formed integrally therewith, the lower edge of the back plate being turned upwardly upon itself, and the lower edge of the cornice being rolled upon 25 the lower edge of the back plate, and a channel formed integrally with the rolled edge of the cornice.

In testimony whereof I affix my signature.

EDWARD M. CLARK.
